UNITED STATES PATENT OFFICE.

LOUIS N. CHADIS, OF NEW YORK, N. Y.

WINDOW-SHADE BRACKET.

1,242,653.

Specification of Letters Patent.

Patented Oct. 9, 1917.

Application filed October 18, 1916. Serial No. 126,382.

To all whom it may concern:

Be it known that I, LOUIS N. CHADIS, a subject of the Czar of Russia, residing at New York, in the county of New York and 5 State of New York, have invented certain new and useful Improvements in Window-Shade Brackets, of which the following is a specification.

This invention relates to window shade fixtures and particularly to the bracket for supporting the end of the shade roller, and has for its object to provide a shade roller bracket which may be secured to any window frame without the use of nails or 15 screws, being retained in place solely by the inherent resiliency of the fixture itself.

A further object of the invention is to provide a shade roller bracket adapted to fit against the inner side of the sash holding 20 strip and having a spring attachment to enter the runway for the sash and bear with sufficient force against the outer edge of the sash holding strip and the inner edge of the parting bead to retain the bracket in place 25 and prevent the same being displaced by the operation of raising and lowering the shade.

With the above as the principal objects in view, the invention consists of the novel 30 construction and arrangement of parts hereinafter described, pointed out in the claims and illustrated in the accompanying drawings, in which:—

Figure 1 is a face view of the improved 35 fixture in place on a window frame, the window frame being shown in section.

Fig. 2 is a top view of the same parts, the window frame being in section on the line 2—2, and

Fig. 3 is a perspective view of the fixture.

In the drawings, 10 indicates a plate which may be rectangular, circular or any desired form having a socket 11 about the center thereof to receive the bearing pin 45 of the shade roller. This plate when in position is placed flatwise against the inner side of the vertical holding strip *a* for retaining a window sash in place. The outer edge of the plate 10 is bent at a right angle 50 to said plate and is preferably made of such width as to bear against the entire thickness of the holding strip *a* on its outer edge. The right angled portion 12 of the plate 10 projects a short distance above the top of 55 the plate 10 and has a finger 13 extending outwardly therefrom and at a right angle

thereto and to said plate, said finger when the fixture is in position bearing against the outer edge of the horizontal holding strip *b* at the top of the window frame.

From the bottom of the angled portion 12 of the plate 10 there extends a ribbon of spring metal 14 of such length as to permit the same to be folded back and forth upon itself a number of times to form a spring 60 like member 15 that is adapted to fit in the space *c* forming the passage way for the lower sash between the holding strips *a* and *b* and the vertical and horizontal parting beads *d* and *e*. The terminal end of the 65 ribbon 14 is bent flatwise at a right angle to the folded portion of the ribbon to form a finger 16 parallel with the finger 13 and substantially of the same length.

The folds of the spring member 15 are 70 normally so inclined with relation with each other that the fingers 13 and 15 are spaced apart a distance much greater than the width of the runway *c* so that when the bracket is placed in position the spring 75 member 15 must be compressed to permit the angled portion 12 of the plate 10 and the finger 13 to bear upon the holding strips *a* and *b* and the finger 16 with the contiguous portion 17 of the spring member 15 80 to press upon the parting beads *d* and *e*. The ribbon 14 that forms the spring member 15 is made of a metal of sufficient weight and resilience to exert considerable pressure 85 against the holding strips and parting beads, 90 a pressure in fact sufficient to hold the bracket plate in place against the upper end of the strip *a* notwithstanding the downward pull of said bracket when the window shade is lowered.

For the purpose of increasing the frictional contact of the fixture with the window frame, the bearing surfaces of the fingers 13 and 16 the angled portion 12 of the plate 10 and the portion 17 of the spring member are covered with rubber as at 18.

When in use the back of the plate 10 will lie close against the inner side of the holding strip *a* at the top thereof, the other part of the fixture being within the runway *c* of 105 the sash and practically hidden from view, the spring member 15 owing to its compression forces the rubber covered fingers and the parts to which they are attached against adjacent portions of the window frame with 110 sufficient force to securely hold the plate 10 in operative position without requiring the

use of nails, screws or other fastening means. The fixtures may be quickly and easily removed when desired for the purpose of cleaning, painting or for any other cause 5 and are easily replaced, and furthermore the window frame is not defaced by use of this fixture because of the absence of nails or screws.

What is claimed is:—

- 10 1. A curtain shade bracket comprising an angle plate having a roller socket on one side thereof and adapted to bear against the inner side of the retaining strip for a window sash, and a spring member comprising a folded ribbon of resilient material secured to said angle plate and adapted to be seated within the sash run-way and hold said plate in operative position.
- 20 2. A curtain shade bracket comprising an angle plate having a socket on one side for a curtain roller pintle and adapted to bear against the inner side of the retaining strip of a window sash, a spring member formed of a ribbon of resilient metal folded back and forth upon itself and secured at one end to said plate, said spring adapted to be seated within the run-way of a window sash and bearing against the parting bead to hold said plate in position, said angle plate and 25 spring member each having a projecting finger to bear respectively against the inner surface of said runway at the top of the window frame.
- 30 3. A window shade bracket comprising an angle plate adapted to bear upon the side and exterior facing edge of a sash holding strip, and a ribbon of resilient metal connected at

one end to said angle plate and folded back and forth upon itself and adapted to bear at its other end against the inner side of the 40 sash parting bead, the intermediate folded portion of said ribbon forming an expandable spring to fit within the sash run-way of the window frame and hold said angle plate frictionally in place. 45

4. A window shade bracket comprising a plate adapted to bear against the side of the sash holding strip of a window frame and provided with a socket for the pintle of a shade roller, an angular extension on one 50 edge of said plate designed to bear upon the exterior facing edge of said strip, an integral bearing finger on said angular extension and lying in the same plane perpendicular thereto, a spring member formed of a ribbon 55 of resilient metal folded back and forth upon itself connected at one end to said angular extension and adapted to bear at its opposite end against the inner side of the sash parting bead, the folded portion of said 60 spring arranged to lie within the sash runway of the window frame, a finger on the outer end of said spring formed by bending the metal of the spring to lie parallel to the first named spring, and a friction cushion 65 secured to the angle plate, the end of the spring, and to both fingers.

In testimony whereof I affix my signature in presence of two witnesses.

LOUIS N. CHADIS.
